TIE PLATE

Filed July 14, 1926

Patented Nov. 30, 1926.

1,608,507

UNITED STATES PATENT OFFICE.

GEORGE M. HOGAN, OF CHICAGO, ILLINOIS, ASSIGNOR TO SELLERS MANUFACTURING COMPANY, OF CHICAGO, ILLINOIS, A CORPORATION OF ILLINOIS.

TIE PLATE.

Application filed July 14, 1926. Serial No. 122,286.

This invention relates to an improved tie-plate as used by railroads for supporting the rails upon the wood ties. These plates provide a broad supporting surface for the rail, and prevent the rail from working down into the ties, and also assist the spikes in transferring the lateral thrusts of the rails to the ties, and hence to the roadbed.

10 It is not unusual to camber or arch the upper face of the plate in a direction longitudinal of the rail supporting surface so as to accommodate the wave-motion of the rail as the load rolls thereover. It is also 15 customary to provide ribs or projections of some sort on the lower face of the tie plate, which are pressed into the wood tie and hold the plate against lateral movement. These ribs are usually of a wedge shaped 20 cross section, and the fairly sharp corners formed where the base of the rib emerges from the flat bottom surface of the plate, act to grip the wood which has been compressed between adjacent ribs, whereby the 25 fibre is severed and the wood is broken away from the tie.

According to this present invention, the plate is not only arched or cambered on its upper surface, but is correspondingly 30 cambered on its lower surface so that the plate will be of substantially equal thickness from side to side thereof. For reasons hereinafter explained, the lower camber will usually be somewhat greater than the upper camber. A plurality of crossed 35 or intersecting ridges are formed on the lower surface of the plate, the projecting edges of these ridges lying substantially in the plane of the side edges of the plate. In other words, these ridges will have a total 40 height varying from zero at the edges of the plate to the height of the total curvature of the lower camber at the center of the plate. The widely flaring curved sides 45 of these ridges merge into the bottoms of the cupped shallow depressions formed between the ridges. The bottoms of these 50 depressions are substantially tangent to, or form part of the lower cambered surface of the tie-plate. These shallow curved depressions will not grip the fibres of the 55 wood so as to break them loose, and the low, wide spreading ridges will be forced into the wood without cutting the fibres. The suction created in the shallow rounded de-

pressions will assist the embedded ridges in effectively preventing lateral movement of the plate on the tie.

One object of the invention is to provide a simple, efficient and durable tie plate, 60 having an improved tie-engaging surface adapted to grip the tie and prevent lateral movement of the plate thereon without unduly injuring the tie.

Another object is to provide a tie plate 65 having an arched or cambered upper rail supporting surface, and a lower surface adapted to evenly engage the flat upper surface of a tie, but so recessed that a substantially even distribution of metal is effected 70 throughout the area of the tie plate.

Another object is to provide an improved tie plate of the character noted above, which may be easily and economically manufactured, and which is lighter, that is, requires 75 less metal than those heretofore in use, without sacrificing strength or rigidity.

Other objects and advantages of this invention will be more apparent from the following detailed description of one approved form of the tie plate.

In the accompanying drawings:

Fig. 1 is a plan view of the tie plate in use between a rail and tie.

Fig. 2 is an enlarged plan view of the lower or tie-engaging surface of the plate.

Fig. 3 is a longitudinal vertical section taken substantially on the line 3-3 of Fig. 2.

Fig. 4 is a transverse vertical section 80 taken substantially on the line 4-4 of Fig. 2, that is, in a direction longitudinal of the rail-supporting surface.

Fig. 5 is a view similar to Fig. 4 (partially broken away), and taken substantially on the line 5-5 of Fig. 2.

Figs 6 and 7 are similar vertical sections taken substantially on the lines 6-6 and 7-7, respectively, of Fig. 2.

As indicated in the drawings, the tie plate 1 is of the usual rectangular outline, having an upper rail-supporting surface 2, side flanges 3 and 4, and being punched at 5 to accommodate the spikes 6, whereby the plate 1 and the rail 7 are anchored to the tie 8. An upstanding rib or shoulder 9 bears against one side edge of the rail base, (usually the outer side of the rail), to take up the spreading thrust imparted to the rail 10 by the trains passing thereover. All of the 110

above is of the usual approved construction. The upper rail-supporting surface 2 is cambered or arched in a direction longitudinal of the rail and of the rib 9, the amount or curvature of this camber being indicated at x in Fig. 4.

The lower surface of the plate is also substantially arched or cambered, as indicated by the dotted line 10 in Figs. 4 and 7. The amount or curvature of this camber is indicated at y in Fig. 4, and it will be noted that this camber is usually greater than the camber x of the upper surface, for reasons hereinafter explained.

The lower surface of the plate does not actually conform to the curved surface indicated by dotted line 10, since this lower surface is provided with a plurality of crossed or intersecting ridges 11, which form a checker-board pattern as indicated in Fig. 2. These ridges have widely flaring or diverging curved sides, which merge into the bottom surfaces of the shallow cupped depressions 12, the edges of which are defined by these intersecting ridges.

Each of these depressions 12 is cupped out in such manner that no sharp angles or corners are present in any portion of the depression. While the exact curves used may be varied, it is preferable to have the depressions curved from side to side as an arc of a large circle, as indicated in Fig. 6. The corners which might otherwise be formed at the junction of the two crossing cylindrical surfaces, are filled in as indicated in Fig. 7, at 13, so that the entire shallow depression approaches closely to a section of a spherical surface, which is slightly distorted so that the ridges 11 which outline the depression will form a rectangle with the projecting edges of the ridges lying in the plane of the lower side edges of the tie plate.

It will be noted that the depressions 12 at the center of the plate are deeper than those at the side edges of the plate, the bottoms of all of these depressions being tangent to, or forming part of the imaginary curved or cambered surface 10, all as clearly indicated in Figs. 4, 5 and 7. The result is to approximate a lower curved or cambered surface provided with a series of outstanding ridges, the projecting edges of these ridges all lying in the plane of the side edges of the tie plate. Since the lower curvature or camber y is greater than the upper curvature or camber x , the thickness of the main portion of the tie plate will be somewhat greater at the edges of the plate than at the center. However, the projecting ridges 11 are higher and thicker at the center of the plate than near the edges thereof, so that the total amount of metal and strength of the plate, is approximately the same at the center as at the edges. The

lower surface of the tie plate, instead of being provided with sharply projecting ribs, is provided with a mildly fluted or wavy surface, the projecting portions of which will be embedded in the wooden tie 73 by the load sustained thereon, without cutting or unduly injuring the fibre of the wood. Since there are no corners in the depressions to grip the embedded wood, but this wood is merely compressed to varying 75 degrees by the gradually rounded bottoms of the depressions, there will be substantially no tendency to break loose the embedded portion of the tie. At the same time, the interlocking surfaces, aided by the 80 suction created in the cupped depressions 12, will be ample to prevent lateral movement between the tie and tie-plate.

It is desirable in the interests of economy, to reduce the weight or amount of metal used in each tie plate as much as can be done, without sacrificing the strength or rigidity of the plate. To do this, it has been customary heretofore to hollow out portions of either the upper or lower surfaces of the plate, to remove metal where it was believed that the same could best be spared. It will be noted that in this improved tie plate the desired arch or camber has been provided upon the upper surface of the plate, and at the same time material has been removed from the lower surface of the plate in such manner as to provide an improved gripping surface, and at the same time approach a cambered lower surface, similar in curvature to that of the upper rail-supporting surface. The plate is of substantially uniform strength and thickness throughout, a minimum of material is used, and the tie-engaging surface 100 is so designed as to firmly grip the tie without injuring it.

This form of plate may also be rolled from thinner material, since, due to the cambered construction, the actual thickness of the metal throughout the plate is considerably less than the apparent over-all thickness of the plate. At the same time, the arched construction formed by the intersecting ridges strengthens the central portion 115 of the plate, so there is no likelihood of the plate flattening out under loads.

Some of the broader features of this invention are disclosed and claimed in my co-pending application Serial 108,049, filed 120 May 10, 1926, the claims in this present application being limited to the features of improvement over said prior invention.

I claim:

1. A tie-plate having its rail-supporting surface longitudinally cambered, and having its tie-engaging surface formed with a plurality of depressions the bottoms of which substantially form a surface of curvature similar to the camber of the plate. 130

2. A tie-plate having its rail-supporting surface longitudinally cambered, and having its tie-engaging surface formed with a plurality of hollow cupped depressions the bottoms of which are substantially tangent to an imaginary surface of curvature similar to the camber of the plate.
3. A tie-plate having its rail-supporting surface longitudinally cambered, and having its tie-engaging surface formed with a plurality of shallow cupped depressions the bottoms of which are substantially tangent to an imaginary surface approximately parallel to the upper cambered surface of the plate.
4. A tie plate having its upper and lower surfaces similarly cambered, the lower surface being provided with a series of projecting ridges which define shallow depressions therebetween, the projecting edges of the ridges lying in substantially the same plane, and the bottoms of the depressions being substantially tangent to the lower cambered surface of the plate.
5. A tie-plate having its upper and lower surfaces similarly cambered, the lower sur-
- face being provided with a series of projecting ridges which define shallow depressions therebetween, the projecting edges of the ridges lying in substantially the same plane, and the bottoms of the depressions forming the lower cambered surface of the plate.
6. A tie-plate having its upper and lower surfaces similarly cambered, the lower surface being provided with a series of intersecting ridges which outline shallow depressions therebetween, the projecting edges of the ridges lying in substantially the same plane, and the bottoms of the depressions forming the lower cambered surface of the plate.
7. A tie-plate having its upper and lower surfaces similarly cambered, the lower surface being provided with a series of intersecting ridges which outline shallow depressions therebetween, the projecting edges of the ridges lying in substantially the same plane, and the bottoms of the depressions being substantially tangent to the lower cambered surface of the plate.

GEORGE M. HOGAN.
